(57) **CLAIM**

The ornamental design for the screwdriver handle, as shown and described.

DESCRIPTION

FIG. 1 is a top perspective view of a screwdriver handle embodying my new design.

FIG. 2 is a front end view of the screwdriver handle of FIG. 1;

FIG. 3 is a right side elevation view of the screwdriver handle of FIG. 1;

FIG. 4 is a left side elevation view of the screwdriver handle of FIG. 1;

FIG. 5 is a rear end view of the screwdriver handle of FIG. 1;

FIG. 6 is a top plan view of the screwdriver handle of FIG. 1;

FIG. 7 is a bottom plan view of the screwdriver handle of FIG. 1; and,

FIG. 8 is a bottom perspective view of the screwdriver handle of FIG. 1.

The stipple on the drawings is for the purpose of shading and not surface ornamentation.
